SELECTIVE HYDROGENATION

William Thomas House, Baton Rouge, La., and Rhea N. Watts, deceased, late of St. Francisville, La., by Beulah Smith Watts, legal representative and sole heir, St. Francisville, La., assignors to Esso Research and Engineering Company, a corporation of Delaware
No Drawing. Filed Feb. 6, 1963, Ser. No. 257,365
8 Claims. (Cl. 260—617)

The present invention relates to an improved process for the hydrogenation of oxygenated compounds and is a continuation in part of S.N. 94,641, filed March 9, 1961, now abandoned. More specifically this invention relates to the selective hydrogenolysis of secondary alcohols from a mixture of alcohols to form paraffins in the presence of particular catalysts at temperatures in the range of 450 to 550° F., at hydrogen pressures in the range of 1000 to 4000 ps.i.g. In one embodiment this invention relates to selectively hydrogenolyzing secondary alcohols to paraffins in the presence of primary alcohols using a molybdenum sulfide catalyst. In another embodiment this invention relates to selectively hydrogenolyzing a secondary alcohol group from a single molecule containing both primary and secondary alcohol groups using a molybdenum sulfide catalyst. In one preferred embodiment the concept of this invention may be applied to selectively hydrogenolyze, in the presence of molybdenum sulfide catalyst, a mixture of alcohols obtained from telomerizing methanol with ethylene to thus remove the secondary alcohols obtained in the process. By this latter process a pure primary alcohol is obtained. In another preferred embodiment a mixture of oxygenated products obtained, for example, from the air oxidation of paraffins is hydrogenated and selectively hydrogenolyzed, in the presence of a molybdenum sulfide catalyst, to yield a mixture of primary alcohols and paraffins.

Prior to the present invention the selective hydrogenolysis of secondary saturated alcohols from a mixture of saturated alcohols to paraffins was practically unknown in the art. Thus according to most text books such a hydrogenolysis was believed to be feasible only when labilizing groups (i.e. carbon-carbon unsaturation, carbonyl groups or hydroxyl groups) were adjacent to the hydroxyl function, and not at all with materials not containing these labilizing groups. The only known hydrogenation of these latter materials to paraffins is described in an article in Chem. Listy, volume 50, pages 569-572 (1956). In this article the hydrogenolysis of tertiary, secondary and primary alcohols is disclosed, all obtained with about the same selectivity under similar conditions. No mention of selective hydrogenolysis of secondary alcohols admixed with primary alcohols was disclosed.

It has now been surprisingly discovered that secondary alcohols may be selectively hydrogenolyzed in the presence of primary alcohols, without any substantial losses of primary alcohols, by utilizing specifically a molybdenum sulfide catalyst. This process is particularly attractive for use in processes wherein synthetic alcohols are produced by telomerization. In this process the product comprises a mixture of primary and secondary alcohols which vary in chain length from a few carbon atoms to 25 carbon atoms, together with smaller amounts of hydrocarbons. The valuable products are of course the primary alcohols. Since the separation of primary from secondary alcohols by distillation, solvent extraction or other known means is extremely difficult because of the overlapping of boiling points and solubilities of the components of the telomer product, this process is particularly advantageous.

The alcohols which may be hydrogenolyzed according

2

to the present process are mixtures of C₁-C₃₀ primary and C₃-C₃₀ secondary saturated monoalcohols. These alcohols include both straight and branched chain alcohols and additionally include cyclic alcohols. Examples of these alcohols are methanol, ethanol, normal propanol, isopropanol, normal butanol, isobutanol, the appropriate pentanols, heptanols, hexanols, octanols, nonanols, decanols, hendecanols, dodecanols, tridecanols, eicosanols, etc. Examples of the cyclic saturated alcohols are cyclopentanol, cyclohexanol, cycloheptanol, cyclooctanol, cycloecicosanol, etc. The invention may be applied to treat specific alcohols of these classes or mixtures of these alcohols. Since somewhat different conditions are used depending upon the molecular weight of the alcohols to be hydrogenolyzed, higher selectivities in the hydrogenolysis of secondary alcohols from primary alcohols are obtained where the primary and secondary alcohols are of similar molecular weight. In addition, the hydrogenolysis may be applied to polyols containing mixtures of primary and secondary alcohol groups on a single molecule. Typical examples of glycols which may be utilized in carrying out the process are C₃ to C₃₀ glycols such as 1,3-hexanediol and C₃ to C₃₀ alkyl substituted glycols such as 2-ethyl-1,3-hexanediol.

Where tertiary alcohols are present with the primary and secondary alcohols, these alcohols will also be hydrogenolyzed by the present process. Thus, the tertiary alcohols will be hydrogenolyzed to paraffins and can thus be easily removed from the desired alcohols, i.e. the primary alcohols with the other paraffins formed. These tertiary alcohols again may be C₄-C₃₀ branched saturated monoalcohols corresponding to those described above.

Particularly attractive feed stocks for hydrogenolysis are the telomer alcohol products obtained by telomerizing methanol with a C₂-C₅ olefin, preferably ethylene, in the presence of a free radical initiator. Processes for preparing these alcohols are described, for example, in U.S. 2,668,181. Additionally other methods for preparing telomer alcohol may be utilized to prepare an alcohol feed stock for the present process. Typical compositions of telomer product alcohols may be C₃-C₂₅ alcohols, containing 15-50 weight percent, e.g. 25 wt. percent secondary alcohols, 1-5 wt. percent e.g. 2 wt. percent tertiary alcohols, 10-25 wt. percent e.g. 15 wt. percent hydrocarbon.

The concept of this invention has also been found to be of particular value in the hydrogenation of paraffin oxidation products yielding a predominance of primary alcohols upon the selection of a suitable catalyst in accordance with this invention. Thus, the hydrogenation of paraffin oxidation products with a molybdenum sulfide catalyst not only produces the corresponding alcohols of said oxidation products but also selectively and continuously hydrogenolyzes the secondary alcohols to yield paraffins. The mixture of primary alcohols and paraffins may then be separated by conventional methods and the paraffins recycled to the oxidation stage. The concept of this invention therefore provides an economical route for the preparation of straight chain primary alcohols which are extremely valuable as intermediates in the production of plasticizers and detergents.

The paraffin oxidation products utilized in conjunction with this invention may be obtained by any of the well known techniques for oxidation of paraffinic petroleum fractions such as crude scale wax and petrolatum. Hence, both catalytic and non-catalytic oxidation processes may be successfully employed. Suitable catalysts for the air oxidation include aqueous KMnO₄, cobalt soaps and manganese soaps. In a less preferred embodiment boric acid may also be present to obtain higher selectivities to alcohols at the expense of lower selectivi-

ties to primary rather than secondary alcohols. Oxidation temperatures may vary from 200 to 400° F. and preferably 240 to 300° F. Suitable processes for oxidation of paraffins are described, for example, in U.S. Patent 2,121,367.

The normal oxidation sequence of paraffins is known to begin by a free radical attack at random at all secondary carbon atoms of the normal paraffin. The primary oxidation products of this reaction are ketones. One mole of water is also formed per mol of paraffin reacting. Acids are also formed by chain cleavage at positions adjacent to the keto group. Several secondary reactions in the oxidation sequence cause the formation of secondary alcohols and lactones. Thus the typical paraffin oxidation product consists of ketones, acids, secondary alcohols and lactones.

The catalysts used in the present hydrogenolysis process are sulfides of molybdenum.

These catalysts may of course be supported on inert carriers of any of the readily available types. Thus, examples of carrier materials which may be used as solid support components of the catalysts are the various alumi-

Using this procedure a complete process for obtaining secondary alcohols from paraffins may be obtained by carrying out the first step air oxidation under the conditions described above, also in the presence of boric acid which directs the oxidation to obtain high selectivities to secondary alcohols.

The present invention will be more clearly understood from a consideration of the following examples.

EXAMPLE 1

The following feed compositions were hydrogenated in a 2000 cc. stainless steel bomb in the presence of catalysts shown, under the conditions described in the following table. The amount of the catalyst used in all runs was 50 volume percent total catalyst based on the alcohol supplied.

Table I

Feed, vol. percent in octanol-1	Temp., ° F.	Holding time, hrs. ¹	Hydrogenation catalyst	H ₂ pres., p.s.i.g.	Percent alcohol destroyed (analyzed by gas chroma- tography)	
					Primary	Secondary
10% Octanol-2	500	6	MoS ₂ ²	3,000	15.5	100
Do	525	6	MoS ₂ ²	3,000	19.0	100
Do	500	3	MoS ₂ ²	3,000	5.6	100
20% Butanol-2	475	6	MoS ₂ ²	3,000	11.5	83.0
Do	500	12	MoS ₂ ²	3,000	31.0	100
Do	475	12	MoS ₂ ²	3,000	16.0	86.0
10% Octanol-2	500	1	MoS ₂ ²	3,000	1.9	59.0
Do	500	1	MoS ₂ ²	3,000	2.2	55.0

⁵ Equimolar mixture

⁷ P.s.i.g. increased with time after heat-up time.

nous and silicious materials of natural or synthetic origin such as bauxite, aluminum oxide, activated alumina, kieselguhr, magnesium oxide, magnesium silicate, magnesium carbonate, barium sulphate, pumice, kaolin, activated carbon, clays, carborundum, alundum, and the like. These catalysts preferably contain 5-25 wt. percent of the active material supported on a carrier of the type above described, e.g. activated carbon. A preferred molybdenum sulfide catalyst has the following general composition: 5-15 wt. percent, preferably 8-10 wt. percent, e.g. 9 wt. percent molybdenum oxide on a carrier of the type above described, e.g. activated carbon, sulfided to saturation with H_2S .

Reaction conditions for the present process are as follows: Temperature, 400-600° F., preferably 450-550° F., e.g. 500° F.; hydrogen pressure, 500-4000 p.s.i.g., preferably 2500-3500 p.s.i.g., e.g. 3000 p.s.i.g.; holding times, 1-15 hours, preferably 1-12 hours, e.g. 3 hours. The amount of the catalyst utilized is 1-16 volume percent, preferably 5-25 volume percent, e.g. 10 volume percent based on the total alcohol supplied.

In a less preferred embodiment primary alcohols may be selectively hydrogenated from secondary alcohols by use of a sulfided cobalt molybdate catalyst under the conditions described above.

EXAMPLE 2

An actual telomer product from telomerization of methanol with ethylene, comprising primarily C_3-C_{25} alcohols with the composition shown below was hydrogenated in a 2000 cc. bomb under the conditions described below. The amount of catalyst used was 50 volume percent based on the telomer product supplied.

Conditions: 500° F., 6 hours holding time, 3000 p.s.i.g.,
 60 H₂·MoS₂ catalyst (as in Example 1).

Heptanol-3/heptanol-1 ratio: ¹

Feed ----- 0.48
Product ----- 0.0

¹ Considered to be a measure of secondary to primary alcohol ratio.

EXAMPLE 3

Cetane, a C₁₆ paraffin feed, was added to a one gallon stirred autoclave and air oxidized under the following conditions:

Catalyst	Mn soap
Wt. percent	0.05 Mn
Temp. ° F.	275
Air rate, liters/hr./100 gm.	30
75 Time, hrs.	11-12

The resulting oxygenated products were analyzed for functional groups by KOH numbers. The KOH numbers are defined as follows: Hydroxyl No. is the mg.

tional groups by KOH numbers both before and after hydrogenation.

The results are summarized below:

	Light acids		Heavy acids and bottoms	
	Oxidation	Hydrogenation	Oxidation	Hydrogenation
Acid No.	212	3	81	5
Hydroxyl No.	72	263	49	120
Ester No.	53	2	49	12
Carbonyl No.	75	-----	81	-----
°API	29.7	43	24.3	39.1

KOH equivalent to acid necessary to esterify 1 g. of material; acid No. is mg. KOH required to neutralize 1 g. of material; ester No. is mg. KOH required to saponify 1 g. of material.

The results are as follows:

Hydroxyl No.	30
Acid No.	125
Ester No.	124
API gravity	23.2

The total oxidation product was hydrogenated in a shaker autoclave in the presence of 50 vol. percent, based on oxidation product feed, of the molybdenum sulfide catalyst of Example 1. The reaction was carried out at 475° F. and a pressure of 3000 p.s.i.g. for a period of 12 hrs. Analysis for functional groups based on KOH numbers resulted as follows:

Hydroxyl No.	148
Acid No.	3.7
Ester No.	59
API gravity	37.2

A temperature programmed gas chromatogram trace on these products indicated a homologous series of normal primary alcohols from C₂ through C₁₄; peaks corresponding to C₆, C₈, C₁₀ and C₁₂ normal alcohols were identified by mixed chromatograms.

The approximate composition calculated from the gas chromatogram was:

Alcohols (C ₂ -C ₁₄)	146
Cetane	35
Heavy products	19

¹ Each alcohol present in 3 to 4% concentration.

This distribution corresponds to approximately 70% selectivity to alcohols, the main non-selective components being the 19% heavy products.

EXAMPLE 4

A cetane feed was oxidized in several runs utilizing different catalysts and temperatures. The catalysts for the several runs were aqueous KMnO₄, manganese soaps and cobalt soaps. Temperatures in the range of 240 to 300° F. were utilized. The oxidation product from each run was distilled and separated into a light acid fraction, a heavy acid fraction, a bottoms fraction and an unreacted feed fraction. The similar fractions from each oxidation run were then contemplated.

The composited light acid fraction and the composited combined heavy acid and bottoms fraction were hydrogenated in the presence of the molybdenum sulfide catalyst and in accordance with the procedure of Example 3 above. Both fractions were analyzed for func-

25 The cleanup of acids and esters by hydrogenation of the light acid fraction is essentially complete. It is somewhat less complete in hydrogenation of the heavy acids including distillation bottoms. From KOH balances calculated for the above hydrogenations selectivity of the hydrogenation for yielding primary alcohols may be demonstrated.

	Hydrogenation feed	Overall KOH balance, percent	Primary KOH balance, percent
30	Light acids	65	101
	Heavy acids and bottoms	45	78

The overall KOH balance is defined by the relationship

$$\frac{\text{KOH numbers of hydro product}}{\text{KOH numbers of hydro feed}} \times 100$$

The primary KOH balance is defined by the relationship

$$\frac{\text{KOH number of hydro product}}{\text{Acid No. and ester No. of feed}} \times 100$$

The overall KOH balance indicates a disappearance of 35 to 55% of the functional groups during hydrogenation. These are the groups that the molybdenum sulfide catalyst hydrogenated to paraffins, e.g. keto and secondary OH groups. The oxidation of paraffins has been theorized to involve a free radical attack on the hydrocarbon chain and thus the alcohols formed during oxidation would be secondary alcohols. The primary KOH balances have been calculated on the assumption that the OH number of the hydrogenation feed represents all secondary functions and the CO number represents all keto functions. The near 100% primary KOH balance indicates that the above assumptions are correct and that 55 the alcohols obtained as hydrogenation product are primary alcohols obtained from the hydrogenation of the acids and esters. The 78% primary KOH balance for hydrogenation of the heavy acids plus bottoms indicates that some functionality other than that represented by 60 the hydroxyl and carbonyl numbers of the feed is lost during hydrogenation. This is undoubtedly the secondary OH groups associated with lactones which show up as esters in the feed.

65 These calculations illustrate very strikingly the selective "scavenging action" of the hydrogenation catalyst for keto, secondary hydroxyl and lactone groups.

EXAMPLE 5

A feed consisting of 2 ethyl-1,3-hexanediol

70 was hydrogenated in a bomb at a temperature of 500° F. and a hydrogen pressure of 3000 p.s.i.g. in the presence

of 50 vol. percent based on feed, of the molybdenum sulfide catalyst of Example 1. The following results were obtained:

Time, Hrs.	Conversion, percent	Selectivity to 2-ethylhexanol
3-----	90	32%(mol.) (CH ₃ —CH ₂ —CH ₂ —CH ₂ —CH—CH ₂ —OH)
6-----	100	28%

The remaining products after the above described hydrogenolysis were paraffins.

EXAMPLE 6

A C₆—C₁₀ alcohol fraction representing about 55 volume percent of the crude, cetane-free product from hydrogenation of the light acid fraction of Example 4 was obtained by vacuum distillation. This alcohol represented an average carbon number of 7.6, was water-white, and had an odor very similar to normal octanol. The infrared spectrum was virtually identical to normal octanol except for a small absorption in the carbonyl (ester) region. No evidence for the presence of secondary alcohols was detected.

This alcohol fraction was esterified with phthalic anhydride using an excess of the anhydride because it was desired to convert all alcohols to esters and recover any non-alcohol impurities for further study. The rather severe esterification and stripping conditions (to remove phthalic anhydride) gave a medium yellow ester. Optimum esterification conditions and normal decolorization procedures should give good color esters. An infrared trace on the recovered esters was essentially identical to a reference spectrum for normal octyl to normal decyl phthalate, except for trace absorption attributed to residual phthalic anhydride. The recovered stripings indicated the original fraction contained about 12% non-alcohol impurities, mainly light esters and hydrocarbons. Preliminary plasticizer evaluations on these esters indicate that their properties are generally comparable to those of diisooctyl phthalate and di-2-ethylhexyl phthalate, which are obtained by esterification of linear primary alcohols.

The above tests indicate that hydrogenolysis with a molybdenum sulfide catalyst selectively yields a primary straight chain alcohol from a mixture containing both primary and secondary functional groups.

It is to be understood that this invention is not limited to the specific examples which have been offered merely as illustrations, and that modifications may be made without departing from the spirit of this invention.

What is claimed is:

1. A process for selectively hydrogenating a mixture of C₁ to C₃₀ primary monohydric alcohols and C₃ to C₃₀ secondary monohydric alcohols which comprises contacting a mixture with hydrogen in the presence of 1 to 60 volume percent, based on said alcohols, of a molybdenum catalyst at a pressure in the range of 1,000 to 4,000 p.s.i.g. and a temperature in the range of 400 to 600° F. for a

period of 1 to 15 hours and recovering a mixture of products consisting essentially of primary alcohols and paraffins.

2. The process of claim 1 where the alcohol feed comprises C₄ to C₃₀ tertiary alcohols in addition to said primary and secondary alcohols.

3. The process of claim 1 wherein said mixture of alcohols is obtained from the telomerization of methanol with ethylene and contains 15-50 wt. percent of secondary alcohols, 1-5 wt. percent of tertiary alcohols, 10-25 wt. percent hydrocarbons, the remainder being primary alcohols.

4. The process of claim 1 in which the catalyst is a 5-15 wt. percent molybdenum oxide on an inert support catalyst sulfided to saturation with H₂S.

5. The process of claim 4 in which the catalyst is supported on activated carbon.

6. The process of claim 4 wherein said mixture of oxygenated compounds is obtained by the oxidation of paraffinic petroleum fractions.

7. A process for producing C₁ to C₃₀ primary alcohols by selective hydrogenation of a paraffin oxidation product which comprises contacting said paraffin oxidation product obtained by air oxidation of a paraffin in the presence of a catalyst selected from the group consisting of aqueous KMnO₄, cobalt soaps and manganese soaps at temperatures in the range of 200° to 400° F., with hydrogen in the presence of 1 to 60 volume percent based on total alcohols in said paraffin oxidation product of a molybdenum sulfide catalyst at a pressure in the range of 1000 to 4000 p.s.i.g. and a temperature in the range of 400° to 600° F. for a period of 1 to 15 hours and recovering a mixture of products consisting essentially of primary alcohols and paraffins, separating said mixture of alcohols and paraffins and recycling said paraffins to said air oxidation step.

8. A process for selectively hydrogenating a C₃ to C₃₀ polyol containing both primary and secondary hydroxyl groups in a single molecule which comprises contacting said polyol with hydrogen in the presence of 1 to 60 volume percent, based on said polyol, of a molybdenum catalyst at a pressure of 1,000 to 4,000 p.s.i.g. and a temperature in the range of 400 to 600° F. for a period of 1 to 15 hours and recovering a primary alcohol.
